UNITED STATES PATENT OFFICE.

WILLIAM GERRY KEENE, OF LYNN, MASSACHUSETTS, ASSIGNEE, BY MESNE ASSIGNMENTS,
TO MORLEY BUTTON MANUFACTURING COMPANY, A CORPORATION OF MAINE.

TAG.

No. 913,732.

Specification of Letters Patent.

Patented March 2, 1909.

Application filed September 27, 1907. Serial No. 394,827.

To all whom it may concern:

Be it known that I, WILLIAM GERRY KEENE, a citizen of the United States, and resident of Lynn, in the county of Essex and State of Massachusetts, have invented new and useful Improvements in Tags, of which the following is a specification.

My invention relates to tags, designed particularly to be used as markers for garments and the like, while the same are being laundered.

It is customary in laundries to apply the owner's identifying laundry mark directly to the garment to be laundered, thus often 15 times disfiguring the garment.

The object of my invention is to provide a tag or marker on which the laundry mark may be inscribed and which may readily be affixed to the garment so that the garment 20 itself shall not be written upon; which may be left permanently on the garment or removed after it has been laundered, as desired; which shall be so thin and flat as not to interfere with the laundering of the garment, and which can be produced at a suffi- 25 ciently low cost to warrant throwing away the marker if it is desired to remove and discard it after the garment has been laundered.

30 The accompanying drawings illustrating certain embodiments of my invention:—Figure 1 is a perspective view of a tag containing my invention; Fig. 2 is a perspective view of one of the fasteners shown in Fig. 1; Fig. 3 is a cross section through the tag, fastener and material to which it is attached; Fig. 4 is an end view of a modified form of tag containing my invention; and Fig. 5 is a cross section illustrating still another form 35 of my invention, the tag being attached to the material.

Referring to the drawings, 1 represents a strip of flexible fabric, preferably made of some material well adapted to receive writing and adapted to withstand washing. At 40 each end of this strip of fabric is a fastener made of an integral piece of sheet metal and comprising a flat bridge part 2, a pair of short prongs 3, 3 at either side of the bridge part and about midway between the ends thereof, and the relatively longer prongs 4, 4 at each end of the bridge part, and upturned in the same direction as the prongs 3, 3. These fasteners are permanently se-

cured to the strip of fabric 1 by piercing 55 the fabric with the prongs 3, 3 and bending the prongs inwardly, clenching them on the under side of the strip. The prongs 3, 3 are together sufficiently longer than the width of the bridge part 2 so that when 60 clenched under the strip of fabric they will meet but not overlap each other, thus avoiding a bunch and providing as flat an article as possible. In the preferred form of my device the bridge part 2, which extends 65 crosswise of the strip 1, reaches approximately to, but slightly short of, the edges of the strip. The bent prongs 4, 4 then pierce the strip 1 thus assisting to keep the strip flat and to prevent it from curling or rolling 70 while it is being manipulated and applied to the garment, and also affording an additional fastening means between the fastener and the strip. It is also within the contemplation of my invention, however, that the 75 bridge part 2 may extend completely across the fabric 1, as shown in Fig. 4, so that the prongs 4, 4 project downward at the sides of the strip 1 instead of perforating the same. In either form the essential feature 80 of the bridge part is preserved; namely, a flat stiffening means or reinforcement is provided which holds the strip flat, both when applying it to the garment, and especially 85 when the tag is affixed to the garment and the garment is being laundered. The bridge part of the present invention overlies the strip of fabric substantially throughout its entire breadth and thus holds it out flat in place. Furthermore, in my preferred form 90 95 of the tag is being handled and when it is being laundered.

The length of the prongs 4, 4 may be varied; they may be sufficiently long for one to overlap the other, as shown in Fig. 3, or they may be, if desired, of such length as to meet in the middle, as shown in Fig. 5. In the latter case I prefer to bend the points 100 inward so that they slightly pierce and are embedded in the material 5, to which the tag is attached as shown in Fig. 5. In this way all sharp points whatsoever, on the surface of the article which could possibly interfere 105 with the laundering of the garment, or catch or injure the fabric or the hands of the operator, are avoided, and an article of the

greatest procurable thinness and flatness is provided.

I claim:

1. As a new article of manufacture, a tag comprising a strip of fabric having a fastener at each end thereof, said fastener having a bridge part extending crosswise of the strip and adapted to hold the strip flat, a pair of short prongs extending laterally one 10 from each side of the bridge part, piercing said strip and clenched to meet end to end thereunder permanently to secure the fastener to the strip, and a pair of flexible prongs one at each end of the bridge part upturned 15 in the same direction as said short prongs, adapted to pierce the material to which the tag is to be applied and secure the tag thereto.
2. As a new article of manufacture, a tag 20 comprising a strip of fabric having a fastener at each end thereof, said fastener having a flat bridge part extending crosswise of the strip and adapted to hold the strip flat, a pair of short prongs extending laterally 25 one from each side of the bridge part, piercing said strip and clenched thereunder, permanently to secure the fastener to the strip, the length of said prongs together being no greater than the width of said bridge part 30 whereby they will not overlap when clenched under the strip, and a pair of flexible prongs one at each end of the bridge part upturned in the same direction as said short prongs, adapted to pierce the material to which the 35 tag is to be applied and secure the tag thereto.
3. As a new article of manufacture, a tag 40 comprising a strip of fabric having a fastener at each end thereof, said fastener having a flat bridge part extending crosswise of the strip approximately to but slightly short of the edge of the strip; adapted to hold the strip flat, a pair of short prongs extending laterally one from each side of the 45 bridge part piercing said strip and clenched to meet end to end thereunder, permanently to secure the fastener to the strip, and a pair of flexible prongs one at each end of the
- bridge part upturned in the same direction as said short prongs, piercing said strip near 50 the edges thereof, and adapted to secure the tag to the material to which it is to be applied.
4. As a new article of manufacture, a tag 55 comprising a strip of fabric having a fastener at each end thereof, said fastener being made of an integral piece of sheet metal having a flat bridge part extending crosswise of the strip, approximately to but slightly short of the edges of the strip, 60 adapted to hold the strip flat, a pair of short prongs extending laterally one from each side of the bridge part, piercing said strip and clenched thereunder permanently to secure the fastener to the strip, the length of 65 said prongs together being no greater than the width of said bridge part whereby they will not overlap each other when clenched under the strip, and a pair of flexible prongs 70 one at each end of the bridge part upturned in the same direction as said short prongs, piercing said strip near the edges thereof and adapted to secure the tag to the material to which it is to be applied.
5. In combination with the material of a 75 garment or the like, a tag or marker comprising a strip of fabric; a fastener at each end thereof having a flat bridge part extending crosswise of the strip, adapted to hold the strip flat against said material; a 80 pair of short prongs extending laterally one from each side of the bridge part piercing said strip and clenched thereunder permanently to secure the fastener to the strip; and a pair of prongs one at each end of the 85 bridge part piercing said material, and bent flat thereunder and having their points inwardly turned and embedded in said material.

Signed by me at Boston, Suffolk county, 90 Massachusetts, this twenty-fifth day of September, 1907.

WILLIAM GERRY KEENE.
